MINE SIGNAL STATION

Robert C. Koomans, Noranda, Quebec, Canada

Application March 25, 1935, Serial No. 12,791

6 Claims. (Cl. 177—339)

This invention relates to an electrical signalling device which is particularly adaptable for use as a mine signal station employed to transmit and give signals to the hoisting engineer from any one of the various levels in the mine.

The invention has as an object a mine signal station comprising a manual operable switch, a visual signal, and an audible signal enclosed in a suitable housing.

10 The invention has as a further object, a mine signal station of such construction that the switch unit, the visual signal means, and the audible signal means are contained in a housing and may be readily removed and replaced without the use of any tools, and whereby the station may comprise a switch unit only, or in combination with either the visual signal means, or the audible signal means, or both.

20 The invention consists in the novel features and in the combinations and constructions herein-after set forth and claimed.

In describing this invention, reference is had to the accompanying drawings in which like characters designate corresponding parts in all the views.

Figure 1 is a longitudinal, sectional view of the mine signal station housing with the switch unit, visual and audible signal units in elevation.

Figure 2 is a top plan view of the signal station 30 with the cover removed, and the switch unit and audible signal unit partially broken away.

Figures 3, 4 and 5 are cross sectional views, taken on lines 3—3, 4—4, 5—5, Figure 1 respectively.

35 Figure 6 is a diagrammatic view showing a plurality of stations at different mine levels, all being interconnected.

Figure 7 is a diagrammatic view of the electrical circuit through the signal station.

40 It will be understood, by those skilled in the art, that some type of signalling system is necessary in deep mines in order that the miners at the various levels in the mine may signal the hoisting engineer and he, in turn, indicate in what manner the cage, or elevator, is about to be moved.

45 In some mines, a manually operable switch is located at each level of the mine adjacent the shaftway, and the switch is operated to transmit a signal to the hoisting engineer. Generally, however, it is preferred to have some form of interconnected signalling system so that the signal, given at any particular level in the mine, is indicated at all other levels as well as in the hoisting engineer's room and preferably, such a system 50 as will also permit the hoisting engineer to indi-

cate in what manner he is about to move the mine cage. The signal station, to which this invention relates, is intended for use in the latter type of system.

The invention comprises generally, a suitable housing, means mounted in the housing and operable, when electrically energized, to give a visual and audible signal, a normally open energizing circuit connected to said signal means, and a switch mounted in the housing and operable from the outside thereof to close said energizing circuit.

5 Referring to Figures 1 and 2, 10 designates a housing which is preferably formed of cast metal and is in the general shape of an elongated box of substantially square cross section, and having an open side opposite the bottom wall 11. The upper edges of the side walls 12, 13, and end wall 14, are provided with an outwardly extending flange 15 forming a margin 16 about the opening in the upper or face side of the housing. The 10 housing is provided with a suitable cover which is preferably secured to the housing without the aid of screws, or like fastenings.

15 As here shown, the cover 17 is formed of sheet metal, the sides and one end of which are bent downwardly and inwardly to receive the flanges 15 and permit the cover to be placed on the housing by sliding it downwardly from the end 14. The cover is provided with a suitable handle 20 with which it may be readily manipulated. The 20 bottom wall 11 is provided with suitable legs 21 to permit the station to be secured to the wall, or timbers, in the mine levels. The station is intended to be mounted, as indicated in Figures 1 and 2, with the end 14 upwardly.

25 The lower end wall is provided with an opening or passage 23, the opposite side walls of which are provided with grooves 24 to slidably receive the sides of the flange 25 formed on the body 26 of the switch unit. The passage 23 is open towards the face of the housing 10 to permit the switch unit to be inserted in the passage 23, as indicated in Figures 1, 2 and 3, and is held in position by the cover 17.

30 A plate 30 of insulating material is mounted 35 on the bottom wall 11, and as here shown it is mounted upon the bosses 31 by means of screws 32 passing through the corners of the plate 30 and threading into the bosses whereby the plate 30 is mounted in spaced apart relationship to the bottom wall 11.

35 Bus bars or contact strips 33, 34, 35, are mounted upon the face of the plate 30. The lower ends of the connector strips 33, 34 are connected directly to the terminals 36, 37, and the connector 50

strip 35 is connected to the terminal 38 by the jumper or conductor 39. The switch unit, per se, is somewhat general in form to that shown in patent to Clausen 1,217,707, comprising a slideable stem 40 which is normally maintained in the position shown in Figure 1 by spring tension, and which is slideable in a downward direction by pulling downwardly on the ring 41. The upper or inner end of the stem 40, which extends in the 10 housing 10, is provided with a disk 42 insulated therefrom and which bridges the contacts 44, 45, when the ring 41 is pulled downwardly. Contacts 44, 45, are formed of resilient metal, and the bottom portions engage the contact strips 33, 34, 15 when the switch unit is mounted in the lower end of the housing 10, as shown in Figures 1 and 3.

The audible signal unit indicated generally 50 is detachably mounted in the upper end portion 20 of the housing 10, and consists of an angular frame having a pair of leg portions 51 extending into the housing at right angles to the bottom thereof. The outer edges of the legs 51 may be tapered as at 52. The outer edges of the legs 25 are slidably received by complementary slots or recesses 53 formed on the inner surface of the side walls of the housing 10, Figures 2-5, and extending perpendicular to the bottom wall 11 and opening toward the face of the housing. 30 A buzzer unit 54 is carried by the angular arm 55. An insulating block 56 is secured to the lower ends of the legs 51, and carries a pair of resilient contacts 57, 58, to which the conductors 59 are connected. The free ends of the contacts 35 57, 58, press against the bus bars 34, 35. The bracket carrying the buzzer unit is provided with raised surfaces 60 with which the cover 17 coats to hold the buzzer unit in the housing, and with the contacts 57, 58, pressed against the connector 40 strips 34, 35.

The device is also provided with a visual signal consisting of a removably insertable plate 65 on which is mounted a lamp receptacle 66. The side edges of the plate 65 are formed in the same 45 manner as the side edges of the legs 51 of the buzzer supporting bracket, and are slidably received in corresponding slots 67 formed in the inner surfaces of the side walls of the housing adjacent the slots 53. The plate 65 also carries 50 a pair of suitable contacts 68 which also contact the connector strips 34, 35. The plate 65 is also held in place by the cover 17 with the contacts 68 pressed against the strips 34, 35.

The side walls 12, 13 of the housing are provided with apertures 70 located between the receptacle supporting plate 65 and the lower end 55 of the housing. These apertures 70 are arranged in alignment with the lamp bulb 71 and are closed by a disk 72 of transparent material attached to 60 the sides of the housing by means of the ring 13, screws 74. The object of this construction is to provide a visual signal when the switch 26 is operated, as will be hereinafter described.

It will be observed that the switch unit, the 65 buzzer unit, and the visual signal unit, are each removably insertable in the housing 10, and are secured and held in place by the cover 17. There are no bolts, screws, or other fastening means, employed to secure these devices in the housing 70 10. This feature of my signal unit is of great practical importance. Those familiar with mine operations are well aware of the fact that in many instances corrosion takes place rapidly, and in apparatus that is assembled with screws, 75 or bolts, or the like, the corrosion renders the

disassembly of the device extremely difficult, if not impossible. In view of the fact that it is necessary to have the signalling device in the mine in continuous operation, it is extremely important that a shutdown does not have to be made 5 to effect suitable repairs or replacements in the signalling system.

In the event the switch, or buzzer unit, become defective, or the lamp bulb burns out, it is only necessary to slide the cover 17 upwardly, and 10 any one of the three units may be removed from the housing 10 by simply sliding them out. Extra units can easily be kept in stock, and when one unit is removed from a particular housing, another unit may be inserted without even the 15 necessity of shutting off the signal system. Also, it is extremely advantageous to have the switch unit, audible signal unit, and visual signal unit, contained in a unitary construction which may be mounted in place as a single unit thus saving a 20 large amount of time, and particularly time and material in wiring the circuit to the units.

It is to be understood that these signal stations at the various mine levels are not operated by the miners, or other employees, but only by the 25 cage, or skip, tender. There is usually a separate signal system very similar to that used in connection with elevators in an office building, by which anyone at a particular level may signal to the cage tender that he desires to be transported 30 from that particular level. The cage tender then operates the signal to the hoisting engineer. Accordingly, these signal stations are installed adjacent the mine shaft so that the cage tender can conveniently reach them from the cage, or elevator. With this signal system, both the cage 35 tender and the hoisting engineer are in agreement previous to the movement of the cage.

Figure 7 is a schematic illustration of the electrical circuit in each signal unit. As previously 40 described, the spring contacts 57, 58, associated with the buzzer unit, and contacts 68, associated with the lamp unit, engage the bus bars or connector strips 34, 35, and are held into engagement with the same by the cover 17 coating 45 with the face of the units. The spring contacts 44, 45, associated with the switch unit, engage the connector strips 33, 34.

Figure 6 illustrates diagrammatically one circuit, or method, of wiring and interconnecting a 50 number of my signal stations in such manner that when the switch unit in any one of the stations is closed, a visual and audible signal is given in each of the other signal stations in the various levels of the mines, and also the switch station in 55 the hoisting engineer's compartment.

The feed wire 80 is connected to the terminal 38 of each of the signal stations. This terminal, in turn, is electrically connected to the connector strip 35 through the jumper 39. The return conductor 81 of the feed circuit is connected to the terminal 36, or contact strip 33, of each of the signal stations, and the connector strip 34 of each signal station is connected to the conductor 82 which terminates at the terminal 37 in the hoisting engineer's signal station. It will be observed that the contact strip 35 is hot at all times and accordingly, a hot feed is furnished to both the buzzer and the lamp units. However, the return circuit is incomplete inasmuch as all the contact strips 34 are connected to the conductor 82, and not to the common return wire 81 due to the fact that all 70 of the switches 42 are normally open.

Assuming that the switch unit in the signal 75

station at No. 1 level in the mine is closed, a circuit is completed from conductor 80, contact 38, jumper 39, contact strip 35, through the lamp and buzzer units, contact strip 34, switch contact 45, disk 42, contact 44, to connector strip 33, to the return conductor 81. Thus a circuit is established through the lamp unit and buzzer at No. 1 level. Inasmuch as the hot side of the line is connected to both the buzzer and the lamp units of each signal station, and the connector strips 34 of each unit are interconnected by the conductors 82, the closing of the switch unit in any signal station completes the return circuit for the buzzer and lamp units in each signal station. Continuing with the assumption in the preceding paragraph that the switch of the station at the bottom level is closed, a circuit is established through the lamp unit and buzzer at the intermediate level through conductor 80, bus 35, lamp unit and buzzer to bus 34, conductor 82, to the station at the bottom level through the closed switch thereof to bus 33, to return conductor 81. In like manner, a circuit is completed through the lamp unit and buzzer of each of the upper stations including the engineer's station. In other words, the closing of the switch 42 in any one station completes a return circuit for all of the stations.

The branch three conductor cable enters the passage 84 in the lower end of the box beneath the switch unit. This passage may be threaded to receive a conduit enclosing the cable, or provided with some suitable cable connector.

It will be observed that it is only necessary to run a three conductor cable in the main shaft, mount a signal station in the main level adjacent the shaft, and make the three connections to the cable. The entire signal station may be readily and easily replaced and also, either the lamp 40 buzzer, or switch unit, may be individually replaced without the necessity of employing any special tools and with a main consumption of time on the part of the maintenance man, and without the necessity whatever of shutting down 45 the signal system.

What I claim is:

1. A mine signal station comprising a housing open at one side, a plurality of electrical contacts mounted within the housing, a signal unit, means for removably mounting said unit in the housing with the terminals of the unit engaging certain of said contacts, a switch, means for removably mounting the switch in the housing with its terminals engaging certain other of said contacts, a removable cover member for the open side of the housing and being operable, when in closed position, to hold said signal unit and switch in the housing with their respective terminals in engagement with said contacts.
2. A mine signal station comprising a housing open at one side, a plurality of electrical contacts mounted within the housing, a signal unit, means for removably mounting said unit in the housing with the terminals of the unit engaging certain of said contacts, a switch, means for removably mounting the switch in the housing with its

terminals engaging certain other of said contacts, a removable cover member for the open side of the housing and being operable, when in closed position, to hold said signal unit and switch in the housing with their respective terminals in engagement with said contacts, said switch being operable from the outside of the housing to energize said switch unit. 5

3. A mine signal station comprising a housing open at one side, a plurality of electrical contacts mounted within the housing, a signal unit mounted within the housing, a switch mounted within the housing, a removable cover member for the open side of the housing, said housing and cover member having means cooperable with said signal unit and switch to removably secure said unit and switch in the housing with the terminals of said unit and switch in engagement with said contacts. 10 15

4. A mine signal station comprising a housing open at one side, a plurality of bus bars mounted within the housing on the back wall thereof, a signal unit, means for removably mounting said unit in the housing with its terminals engaging certain of said bus bars, a switch, means for removably mounting said switch in the housing with its terminals engaging certain other of said bus bars and being provided with an operating member extending through and being operable from the outside of said housing, a removable cover member for the open side of the housing and being operable when in closed position for holding the signal unit and said switch in the housing with their respective contacts engaging said bus bars. 20 25 30 35

5. A mine signal station comprising a housing open at one side, a plurality of contacts mounted within the housing, a signal unit mounted in the housing with its terminals engaging certain of said contacts, a switch, means for removably mounting the switch in the housing, a removable cover member for the open side of the housing and being operable, when in closed position, to hold said switch in the housing with its terminals in engagement with certain other of said contacts. 40 45

6. A mine signal station comprising a housing open at one side and having opposite side walls provided with a plurality of grooves extending inwardly from the marginal surface about said opening, a plurality of bus bars mounted within the housing on the bottom wall thereof, a signal unit slidably mounted in one pair of grooves and having its terminals engaging two of said bus bars, a switch slidably mounted in another pair of said grooves and having its terminals engaging one of said first mentioned bus bars and a third bus bar, a cover member slidably mounted on the open side of the housing and being operable, when in closed position, to move said signal unit and switch toward the bottom wall of the housing and hold the contacts of said unit and switch in engagement with the respective bus bars. 50 55 60
